UNITED STATES PATENT OFFICE.

IREDELL SMITH, OF ST. LOUIS, MISSOURI, ASSIGNOR TO CHARLES F. WALLERSTEDT, OF ST. LOUIS, MISSOURI.

POCKET-BOOK.

1,228,251.

Specification of Letters Patent. Patented May 29, 1917.

Application filed May 18, 1916. Serial No. 98,829.

To all whom it may concern:

Be it known that I, IREDELL SMITH, a citizen of the United States, residing at St. Louis, State of Missouri, have invented 5 certain new and useful Improvements in Pocket-Books; and I do hereby declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to new and useful improvements in pocket books and consists in the provision of a simple and efficient device of this nature so arranged that the flaps upon the same afford means for allowing a bill to be properly positioned within the pocket book and prevented from losing out and so arranged that the shaking of the bill fold, when opened out, will dislodge the bill therefrom and, at the same time, permitting bills of different denominations to be extracted without disturbing the other bills that may be held in the pocket book.

20 The invention comprises various details of construction which will be hereinafter 30 fully described, shown in the accompanying drawings and then specifically defined in the appended claim.

I illustrate my invention in the accompanying drawings, in which:—

35 Figure 1 is a plan view showing the sheet of material out of which the pocket book is made.

Fig. 2 is a view showing a bill adjusted in place.

Fig. 3 is a rear view of the pocket book, 40 and

Fig. 4 is a sectional view on line 4—4 of Fig. 1.

Reference now being had to the details of the drawings by letter, A designates a sheet 45 of leather or other suitable material out of which the pocket book is made, and having two semi-cylindrical slits B cut therein, forming the oppositely disposed flaps C underneath which the bill is held in the manner shown in Fig. 2 of the drawings.

50 By the provision of the slits, the fingers are allowed to be passed therethrough and in this way the adjustment of the bills may be facilitated to proper position in order 55 that corresponding ends of the bills may be brought flush with the inner end fold and, when properly placed and folded, the bills will not accidentally be lost from the pocket book and bills of different denominations 60 may be extracted without disturbing the rest of the bills.

What I claim to be new is:—

65 A porte-monnaie comprising a single piece of material having two oppositely disposed flaps cut up therefrom and spaced apart and underneath which a bill is adapted to be placed with the opposite marginal edges thereof bearing against the inner ends of the slits formed by cutting of the flaps.

70 In testimony whereof I hereunto affix my signature in presence of two witnesses.

IREDELL SMITH.
